UNITED STATES PATENT OFFICE.

GUILLAUME CLEMENT LAURENCY, OF TWICKENHAM, ENGLAND, ASSIGNOR OF SIXTY
PER CENT TO GRANT McLEAN, OF LONDON, ENGLAND.

APPARATUS FOR DRAWING TEXTILE FIBERS.

Application filed March 19, 1926, Serial No. 96,039, and in Great Britain June 22, 1925.

This invention relates to drawing apparatus employed for drawing textile fibers used in spinning, in which the fibers are drawn through the needles of a porcupine roller.

The invention provides improvements which facilitate the sliding and distribution of the fibers, rendering it possible to considerably increase the drawing action without interfering with the regularity in the section of the drawn roving, and to hold the shortest fibers as well as those of greatest length until the moment when they are withdrawn from the roving by the front roller.

15 so that the drawing operation can be effected throughout the whole length of said fibers, and so that the shortest fibers as well as the longest, while being still held at one end and drawn at the other end, are straightened and parallelized.

As is generally known, the drawing operation is usually carried out between a series of suitably spaced cylinders and rollers arranged in pairs. The fibers held by the first pair are drawn by the pair which terminates the series (usually called "front rollers" or "drawing cylinders"); the circumferential speed of these front rollers being greater than that of the preceding pairs 30 of rollers, the fibers therefore slide between the intermediate pairs, but the latter must not allow the fibers to slide except when they are drawn by the said front rollers.

To hold the fibers, while allowing them such sliding, the top rollers of the intermediate pairs compress the fibers by their own weight upon the lower rollers; but the distance between the point at which this compression is effected and the point at which the fibers are drawn by the front rollers, is limited by the diameters of the two pairs of rollers, and all the fibers which are not longer than this distance cease to be held by such compression before being drawn by the front rollers; consequently said fibers are drawn along irregularly by those which are moved at the drawing speed, and such uneven distribution produces irregularity in the drawing.

45 This compression by the actual top rollers cannot be exerted over all the fibers which pass at the same time; the fibers which are in the center of the roving are very strongly pressed, while those which are 55 at the sides, and which constitute a much

smaller thickness, are not gripped between the rollers and are drawn along irregularly with the shortest fibers.

These defects are obviated by the present invention by effecting the drawing operation close to the point at which the fibers are held by toothed rollers which form a kind of "filter" adapted to retain the fibers without excessive compression, in such a manner that all the fibers are held and each of them may be separately withdrawn from the mass of the roving without disarranging the others.

In the accompanying drawings:

Fig. 1 is a side elevation, with parts broken away, showing an embodiment of this invention as applied to a frame for spinning cotton and other substances with short fibers of varying length.

Fig. 2 is an end elevation from the right of Fig. 1, likewise with parts broken away and with parts in section.

Fig. 3 shows a modified arrangement of the rollers for drawing roving with short and longer fibers.

Fig. 4 is a front view of certain rollers illustrated in Figs. 1, 2 and 3 in a superposed relation.

The embodiment shown in Figs. 1 and 2 comprises two toothed "filter" rollers A and B provided with special teeth which retain the fibers without, however, preventing their sliding when at drawing speed. Rings A¹ and B¹ of leather, rubber or like friction

material are applied to the ends of said rollers A and B, respectively, and these rings are in contact with rings or collars C¹ on a long intermediate cylinder C which extends through the whole width of the machine. The said collars or rings C¹ are

fluted and transmit the movement of cylinder C to the rollers A and B through contact of their flutes with the said leather rings A¹ and B¹. The top roller D, which may be

smooth or encased in leather as usual, rests on the toothed roller B, and is rotated by permanent contact therewith; that is to say, such contact is never interrupted by the passage of the fibers retained by said roller B.

The rollers A and B may be placed slightly spaced apart, and the cylinder C provided for a positive and regular movement thereof.

The front roller or drawing cylinder F is provided with fine spaced flutes, and the fibers are pressed against said flutes by one

or more metal segments G, so that they are drawn along by the said front roller F. The pressure on said flutes is exerted preferably by two segments at once by means of a 5 spring plate H which bears on a cylindro-conical pivot G¹ located at the center of the plane of each segment. The pressure of the said plate can be adjusted for each segment individually by means of screws J, and the 10 said segments can be removed and replaced without altering the pressure or stopping the machine.

A roving guide consisting of a transverse bar K carrying forks L, which latter regulate the entrance of the roving into the apparatus, has a reciprocating movement with a period of stoppage at each end of its course. The speed of this roving guide is in proportion to the average length of the 20 fibers to be drawn. The reciprocating motion of the bar K can be obtained by various known means; in Fig. 1, this motion is produced by a pulley M carrying an eccentric pin N, and two abutment members P and 25 P¹ which are secured to the bar K and alternately forced one to the right, the other to the left, by the revolution of said pin N. The period of rest of the roving guide at each end of its course is equivalent to the 30 time required for the pin N to pass from one abutment member to the other. The pulley M may be stepped, so that the speed of the roving guide can be varied by transferring the belt which actuates it to a step 35 of a different diameter.

Guided by the fork L, the roving designated by the broken line r enters obliquely between the rollers B and D and forms undulations which are more numerous and consequently at a more acute angle according 40 as the speed of the roving guide L is greater in relation to the circumferential speed of the roller. These undulations are continued on the roller A, and the roving retained between the teeth of rollers B and A advances 45 with these rollers until its foremost end reaches the segment G and is drawn under the latter through the flutes of the drawing cylinder F. From this moment, these fibers 50 are at drawing speed; that is to say, they advance with the cylinder F, the circumferential speed of which is greater than that of the filter rollers A and B, and slide between the teeth of said rollers, becoming 55 separated from those fibers the forward end of which have not yet reached the segment G, and which continue to advance slowly with said rollers A and B.

It will be observed from Fig. 2 that the 60 entrance of the fibers between the segment G and the drawing cylinder F is effected close to the teeth of the roller A. This feature is of importance in the invention since it solves the question of free spaces in the drawing, and the fibers of shortest length 65

only cease to be held by the teeth when withdrawn therefrom by the drawing cylinder. The short fibers are consequently straightened and parallelized as well as the fibers of all other lengths with which they are 70 then agglomerated by twisting on leaving the segment G at the point o.

The fibers being better held by the toothed rollers A and B in proportion as the undulations are more numerous and the average 75 length of the fibers is greater, the speed of the roving guide must, of course, be decreased for long fibers and increased for shorter ones; the fibers are also held the more firmly by the flutes of the drawing cylinder F as their position on said cylinder forms a more acute angle with the flutes thereof, the segment G retaining them more 80 easily in the flutes than when they are placed at right angles with relation thereto.

From these considerations, it follows that slight pressure of the segment G is sufficient to insure the regular traction of the fibers by the drawing cylinder F; and this feature 85 of the invention, in addition to the ease with which the fibers can slide between the teeth of the intermediate rollers A and B when they are drawn by said cylinder F, enables a suitable segment G to be used in combination with a specially-fluted drawing cylinder, to move the fibers regularly at the 90 drawing speed.

Owing to this combination of the segment G with the cylinder F, the toothed rollers A and B can conduct the fibers to the said 95 segment G close to the drawing cylinder which draws them along at an accelerated speed and away from the teeth of rollers A and B with a sliding movement, the shorter fibers and the longer ones being thus drawn, straightened and parallelized throughout their entire length.

The modification shown in Fig. 3 is for drawing fibers of which the greatest length is less than the distance U. This distance 100 must not be shorter than the longest fibers which are in the roving; but it can, of course, be increased by inserting one or more sets formed by a cylinder C², a toothed filter roller A², B² or S, and a top roller D² 105 co-operating with said rollers, all as shown in superposed position in Fig. 4. The pair of usual feeding rollers R, T can also be employed, and all sets of rollers, C² and A², B², C² and S, D² and R, T, can be suitably 110 spaced on the frame Y of Fig. 3.

The roller A of Fig. 2, or A² of Fig. 3, has very inclined teeth and holds the fibers 115 near the drawing cylinder F. This arrangement allows of dispensing with the use of a top roller, the traction exerted by the drawing cylinder F being sufficient in this case to cause the roving to penetrate and be retained in the filter roller A² or B². Consequently, the top roller is not necessary 120 125 130

when the teeth of the filter roller are inclined backwards; but when the teeth are at right angles, like B in Fig. 2, and S in Fig. 3, a top roller maintains the fibers in the filter and it is rotated by the toothed roller on which it rests in permanent contact by its own weight without directly compressing the fibers which are located between the teeth. The top roller D², which 10 may, if desired, also be a toothed roller, merely holds the roving in the filter on a level with the points of the teeth. The roving is no longer crushed between two rollers to prevent the premature advance of the 15 fibers, the resistance necessary to prevent such advance being produced in the filter, the teeth of which penetrate the roving and divide it to facilitate the sliding of the fibers, and such sliding between the teeth compels 20 said fibers to readjust themselves and become parallel when they are pulled out by the drawing cylinder.

I claim as my invention:

1. In apparatus for drawing textile fibers, 25 the combination of a toothed roller forming a filter adapted to retain all the fibers of the roving by means of its teeth alone, a longitudinally-fluted front drawing cylinder located in close proximity to the filter roller, 30 a segment partly surrounding said cylinder, and adjustable spring means for pressing said segment against the flutes of the cylinder; said cylinder acting to draw the fibers separately from the mass of roving, without 35 disarranging the other fibers, by removing them from the teeth of the filter roller and causing them to slide across the inner surface of the segment.

2. Apparatus according to claim 1, in 40 which the ends of the filter roller are furnished with rings of friction material; and in which a driving cylinder is provided having flutes whereon said rings directly rest, whereby said roller is rotated by the contact 45 of such flutes and rings.

3. Apparatus according to claim 1, in 50 which the pressure imposed upon the segment by the adjustable spring means is centralized at one end of a line extending radially outward from the center point of the segment.

4. In apparatus for drawing textile fibers, 55 the combination of a toothed roller forming a filter adapted to retain all the fibers of the roving by means of its teeth alone, a longitudinally-fluted front drawing cylinder located in close proximity to the filter roller, a segment partly surrounding said cylinder, 60 a bearing pin projecting radially outward from the center of the outer face of the segment, a spring member whereon the point of said pin rests for pressing the segment against the flutes of the cylinder, and an adjusting member associated with the spring 65 member for varying the tension of the latter;

said cylinder, acting to draw the fibers separately from the mass of roving, without disarranging the other fibers, by removing them from the teeth of the filter roller and causing them to slide across the inner surface of the 70 segment.

5. In apparatus for drawing textile fibers, 75 the combination, with a drawing cylinder, of a toothed roller located in close proximity thereto and forming a filter adapted to retain all the fibers of the roving by its teeth alone, a cylinder in driving contact with said filter roller to rotate the same, and a top roller resting loosely upon the filter roller and driven thereby.

6. In apparatus for drawing textile fibers, 80 the combination, with a drawing cylinder, of a toothed roller located in close proximity thereto and forming a filter adapted to retain all the fibers of the roving by its teeth alone, said roller having rings of friction material fitted on its ends, a driving cylinder having flutes in contact with said rings to rotate the filter roller, and a top roller resting loosely upon the filter roller and driven 85 thereby.

7. In apparatus for drawing textile fibers, 90 the combination of a toothed roller forming a filter adapted to retain all the fibers of the roving by means of its teeth alone, a longitudinally-fluted front drawing cylinder located in close proximity to the filter roller, a segment partly surrounding said cylinder, 95 adjustable spring means for pressing said segment against the flutes of the cylinder; said cylinder acting to draw the fibers separately from the mass of roving, without disarranging the other fibers, by removing them from the teeth of the filter roller and causing 100 them to slide across the inner surface of the segment; a roving guide, and means for imparting a reciprocating movement to said guide with a period of rest at the end of each stroke, thereby to produce undulations of the roving which cause the fibers to pass at a 105 more or less pronounced angle on the filter roller and between the segment and the flutes of the drawing cylinder.

8. In apparatus for drawing textile fibers, 110 the combination of a finely-fluted drawing cylinder, a segment partly surrounding the lower portion of the periphery of said cylinder; the flutes of said drawing cylinder moving the fibers along and causing them to slide over the inner surface of the segment; and spring means for pressing said segment upward against the flutes of the drawing 115 cylinder.

9. In apparatus for drawing textile fibers, 120 the combination of a finely-fluted drawing cylinder, a segment partly surrounding the lower portion of the periphery of said cylinder; the flutes of said drawing cylinder moving the fibers along and causing them to slide over the inner surface of the segment; 125

- means for resiliently pressing said segment upward against the flutes of the drawing cylinder, and means for adjusting the tension of said pressure means. 35
5. 10. In apparatus for driving textile fibers, the combination of a finely-fluted drawing cylinder, a segment partly surrounding the lower portion of the periphery of said cylinder; the flutes of said drawing cylinder 10 moving the fibers along and causing them to slide over the inner surface of the segment; means for resiliently pressing said segment upward against the flutes of the drawing cylinder, a bearing cone situated at the center point of the segment and whereon said pressure means acts, and means for adjusting the tension of said pressure means. 15
11. In apparatus for drawing textile fibers, the combination, with a pair of superposed, removable fiber-retaining rollers, the surface of the lower roller being provided with pointed teeth to lightly retain the fibers, and the upper roller rolling by its own weight on the lower roller; of a cylinder whereon said lower roller rests adapted to drive the same by friction. 20
12. In apparatus for drawing textile fibers, the combination, with a pair of superposed, removable fiber-retaining rollers, the 30 surface of the lower roller being provided with pointed teeth to lightly retain the fibers, and the upper roller rolling by its own weight on the lower roller; of a cylinder whereon said lower roller rests adapted to drive the same by friction. 25
13. In apparatus for drawing textile fibers, the combination, with a plurality of fiber-retaining rollers, the surface of each being provided with pointed teeth to lightly 40 retain the fibers, and an upper roller rolling by its own weight on certain of the first-named rollers; of a cylinder adapted to drive said first-named rollers by friction, a finely-fluted drawing cylinder receiving the 45 fibers from said rollers, and a segment partly surrounding the periphery of the drawing cylinder and resiliently pressed thereagainst. 50
14. In apparatus for drawing textile fibers, the combination of driving cylinders placed at variable distances apart and the number of which is determined by the maximum length of the fibers, an intermediate fiber-retaining roller engaging each driving 55 cylinder and from which it receives movement, a drawing cylinder receiving the fibers from the last fiber-retaining roller, and a member coacting with the drawing cylinder and pressed thereagainst, said 60 member adapted to be placed at different distances with respect to the point at which the last roller and its associated driving cylinder are in contact. 65

In witness whereof I have signed this specification.

GUILLAUME CLEMENT LAURENCY.
